UNITED STATES PATENT OFFICE.

FRITZ POHLMANN, OF ZURICH, SWITZERLAND, ASSIGNOR TO THE FIRM OF HYDORION
INTERNAT WASCHEREI-MASCHINEN-GESELLSCHAFT, OF ZURICH, SWITZERLAND.

WASHING-MACHINE.

1,002,929.

Specification of Letters Patent. Patented Sept. 12, 1911.

Application filed February 16, 1910. Serial No. 544,270.

To all whom it may concern:

Be it known that I, FRITZ POHLMANN, engineer, a subject of the German Emperor, residing at 37 Streulistrasse, Zurich, Switzerland, have invented certain new and useful Improvements in Washing-Machines, of which the following is a specification.

This invention relates to a washing machine with double drums one inside the other, the inner drum having hollow ribs through which the washing water is introduced under high pressure. The inner drum is free from holes and rough surfaces between the ribs and consequently the linen is not likely to get damaged and the holes in the ribs enable the water to flow freely and thus maintain a good circulation.

I will now describe my invention with reference to the accompanying drawings, in 20 which—

Figure 1. is a side view partly in section of a machine constructed according to my invention. Fig. 2 is an end view of Fig. 1. Fig. 3 is a sectional view on line 3—3 of Fig. 1. Fig. 4 is a detailed sectional view of the valved inlet apparatus discharging from the outer casing 1. Fig. 5, is a longitudinal section of the outer casing and drum. Fig. 6 is a transverse sectional view of the 30 inner drum. Fig. 7 is a view similar to Fig. 5 of a modified form of the invention. Fig. 8 is a transverse section of the form shown in Fig. 7. Fig. 9 is a view similar to Fig. 7 showing a further modification. 35 Figs. 10 and 11 illustrate an improved float controlling device.

The washing machine shown in Figs. 1 to 6 shows an outer drum mounted on pillars 2 inside which a rotatable inner drum 3 is arranged, the said inner drum being rotated independently of the outer drum. The inner drum is arranged with a hollow shaft 4 connected by pipe 5 with the water under pressure, the said pipe leading from 45 two water tanks, 6, 7, and having in it a force pump 8. The tanks 6, 7 are placed close to the outer drum 1 and two discharge pipes 10 lead from the drum to the inlets 11 of the tanks. Each of these inlets is 50 encircled by a ring 9 of tight fitting material on which the end of the pipes fit and to insure this close fitting a pivoted loop 12 is arranged to engage lugs or pivots 13 fixed to the pipe in such a manner as to 55 draw the pipe closely down on to the ring

9 of the material. Each pipe is provided with a throttle valve 14. The inner drum 3 has a chamber 3' at each end formed by the main walls 15 connected with the hollow shaft 4 and the casing 16 which is provided 60 on the inside with hollow axial ribs 17 each arranged about a pipe 18 leading to the two chambers. The ribs 17 and the pipes 18 are provided with bores or outlets 19 of equal size and which coincide so that water 65 may be injected from the chambers through the pipes 18 and into the inner drum. The ribs 17 are provided with holes 20 by which the water can flow from the inner drum into the outer. 70

The tanks 6 and 7 are connected to the pipe 5 by valves 21 and the tank 7 is designed to hold water for rinsing purposes while the tank 6 serves to hold the water which is used for washing. The tank 6 has 75 arranged in it a heating tube 22 and a scum or dirt collector 24 (see Figs. 1, 10 and 11). This collector is in the shape of a float and is provided with a discharge pipe leading to the side of the tank through which the dirty 80 water escapes, the said collector automatically taking away the dirt floating on the surface.

The method of washing may be described as follows: By means of the pump, lye can 85 be drawn from the tank 6 and forced through the hollow shaft into the chambers of the inner drum and from there to the pipes 18 from which it passes in jet-like manner on to the linen in the inner drum 90 and after passing through the clothes escapes from the inner drum by the openings 20 and returns therefrom to the tank 6. During this process the tank 7 is closed and the washing lye may be circulated through 95 the machine as long as desired. By adjusting the valves, rinsing water may be drawn from the tank 7 and used in the washing or the whole process of washing carried out by closing the admission and discharge pipes after the drums have been partially 100 filled.

For the purpose of emptying the drums the arrangement as shown in Figs. 1 and 4 may be employed. This arrangement consists of a neck 25 provided with an adjustable valve 26 which is held by spring pressure. A discharge pipe 29 having an inlet 30 is arranged in the pillar 2 and adapted to meet the neck 25, the said pipe having a 110

spring controlled rod 31 capable of being moved against the valve 26 and opening it, the said rod being held out of engagement by a spring 32.

5 Figs. 7 and 8 show a drum with a central perforated partition 40 dividing the drum into two chambers, the end walls 42 and 43 of which are perforated. The water enters the chambers as indicated by the arrows. 10 Some of the pipes in this modification are without outlet holes to the ribs for the purpose of conveying water to the farther chamber before distribution.

15 Fig. 9 shows three inner chambers the walls of which are perforated and in this case water is introduced at each end of the drum. This arrangement provides means whereby soiled linen may be graded and placed within the chambers according to 20 the activity of the flow of washing material.

Having now particularly described and ascertained the nature of my said invention and in what manner the same is to be performed I declare that what I claim is:—

25 1. A washing machine comprising in combination, an outer casing, a revolvably mounted casing disposed in said outer cas-

ing and provided with inwardly projecting ribs opening outwardly and having inlet 30 openings therein, pipes disposed in said ribs and having openings communicating with said inlet openings, the walls of said ribs having outlet apertures opening to said outer casing, and means for continuously 35 supplying water to said pipes.

2. A washing machine comprising in combination, an outer casing, a revolvably mounted casing disposed in said outer casing and having inwardly projecting ribs 40 provided with inlet apertures, pipes disposed in said ribs and revolving with said inner casing and having openings communicating with said inlet apertures, the walls of said ribs having outlet apertures disposed radially outwardly with respect to 45 said inlet apertures, said inner casing being imperforate and continuously smooth between said ribs, and means for continuously supplying water to said pipes.

In testimony whereof I affix my signature in presence of two witnesses.

FRITZ POHLMANN.
